United States Patent Office

Des. 211,094
Patented May 21, 1968

211,094

TELEPHONE DIAL

Graham S. Laing and Wesley N. Willis, London, Ontario, Canada, assignors to Northern Electric Company, Limited, Montreal, Quebec, Canada

Filed Aug. 22, 1967, Ser. No. 8,346

Term of patent 14 years

(Cl. D26—14)

The figure is a front perspective view of a telephone dial, showing our new design. The broken lines are shown for illustrative purposes only.

We claim:

The ornamental design for a telephone dial, as shown and described.
